UNITED STATES PATENT OFFICE.

FRANK A. BURNHAM, OF CLEVELAND, OHIO, ASSIGNOR TO THE CHANDLER & PRICE COMPANY, OF SAME PLACE.

DESIGN FOR A FRAME FOR PAPER-CUTTERS.

SPECIFICATION forming part of Design No. 27,546, dated August 17, 1897.

Application filed March 6, 1897. Serial No. 626,329. Term of patent 7 years.

To all whom it may concern:

Be it known that I, FRANK A. BURNHAM, of Cleveland, Cuyahoga county, Ohio, have invented and produced a certain new and useful Design for the Framework of Paper-Cutting Machines, of which the following is a specification, reference being had to the accompanying drawings, illustrating the design.

In the accompanying drawings, Figure I is a view in perspective of the framework of a paper-cutting machine embodying my improved design. Fig. II is an outer side elevation of one of the upright side frames of the machine. Fig. III is a top plan in horizontal section on lines III III, Figs. I and II. Fig. IV is a transverse vertical section on line IV IV, Fig. III. Fig. V is a horizontal section on line V V, Fig. II.

Referring to the drawings, A A designate the two upright side frames of the machine. Said frames are located a suitable distance apart. B designates the horizontally-arranged bed or table upon which the paper to be cut is placed. A yoke C connects together the upper ends of the two side frames. The upper portion of each side frame is provided with a lateral and vertical slot 1, formed centrally of the upper portion of said frame above table B. The side walls of said slots 1 constitute guides for the knife-head. (Not shown.)

Each frame A is narrower above the table than below, and the lower extremity of the upper or narrower portion of the frame terminates flush with the upper surface of the table, and the front and rear sides of the lower part of said portion of each side frame diverge and curve, as at 2, toward the wider portion of said frame. The upper or slotted portion of each side frame is approximately quadrangular in cross-section at both the forward and rear sides of the slot in the frame,

as shown in Fig. V. Each side frame, below the table, is shaped to form two parallel perpendicular columns 3 3 below the different sloping surfaces 2 2, respectively, of the frame and connected at the top by a web 4 and at the bottom by a web 5, having a flat upper surface, so as to form a perpendicularly-rectangular space 6 between the two columns that are approximately quadrangular in cross-section, as shown in Fig. III. Each side frame, at its lower end, has two diverging feet 7 and 7, formed at the forward side and rear side, respectively, of the frame below the different columns 3 3, respectively. The forward surface of the forward foot is flush with the forward surface of the forward column, and the rear surface of the rear foot is flush with the rear surface of the rear column. The two side frames are connected together by two horizontal bars 8 8, arranged at opposite ends, respectively, of webs 5 and having their upper surfaces flat and in the same or approximately same horizontal plane with the upper surfaces of said webs. Journal-boxes 9 9 are formed upon the left-hand ends of bars 8 8.

The essential feature of my design consists in the shape or configuration of the said side frames.

What I claim is—

The design for the framework of a paper-cutting machine, substantially as described and illustrated in the accompanying drawings.

In testimony whereof I sign this specification, in the presence of two witnesses, this 13th day of February, 1897.

FRANK A. BURNHAM.
